UNITED STATES PATENT OFFICE

SAMUEL E. SPERRY, OF HOLLIS, NEW YORK, ASSIGNOR TO INTERTYPE CORPORATION,
OF BROOKLYN, NEW YORK, A CORPORATION OF NEW YORK

KEYBOARD MECHANISM FOR TYPOGRAPHICAL MACHINES

Application filed August 24, 1931. Serial No. 559,068.

The present invention relates to improvements in keyboard mechanism for typographical machines of the well known class which employ a magazine containing character-bearing matrices which are released and delivered therefrom under the control of escapements actuated by the keyboard mechanism for assembly in a line and presentation to a mold for the casting of a type bar or slug therefrom, keyboard mechanism of this general class being shown and described in my prior Patent No. 1,734,922 granted November 5, 1929.

Keyboard mechanism of the class referred to comprises continuously revolving rubber covered rolls and cam yokes carrying cams which move, under control of the finger keys of the keyboard, into engagement with the rollers whereby they are operated by power from the rollers to actuate the matrix controlling escapements, there being usually ninety cam yokes in the keyboard mechanism, each cam yoke carrying a rotatable toothed cam which when operated traverses the periphery of the rubber covered roll, and since some of the cams operate more frequently than others so that the teeth thereon wear down unequally and dirt lodges in the bearings of the cams or of the cam yokes, periodical inspection and cleaning is necessary to insure dependable operation of the keyboard mechanism. Proper care and inspection can be assured in the relatively inaccessible location of these parts only by providing the maximum opening for visual inspection and the greatest convenience for examining the parts under normal operation as well as ease of manipulation in removing and replacing the parts.

Heretofore, the cam yokes have been mounted for independent and individual removal from the keyboard frame upon displacement of a clamping or locking bar, an example of a keyboard mechanism of that type being disclosed in the patent to T. S. Homans, No. 1,102,923, granted July 7, 1914. However, in keyboard mechanism of such construction, the cam yokes are relatively close to one another and those at the back of the keyboard are difficult to reach and are

likely to become disengaged from their bearing seats or their triggers when one or another of the cam yokes is manipulated for removal or replacement. Furthermore, after the clamping or locking bar has been displaced, it is no longer possible to test the keyboard mechanism while it is running or operating under power or even to turn the rubber covered rollers by hand while depressing a key lever to detect by visual inspection a faultily operating cam yoke, it being not only desirable but usually necessary to displace the clamping or locking bar to permit visual inspection of the many parts of the keyboard mechanism which are compactly assembled therein and when the clamping or locking bar is displaced, the cam yoke will not be actuated in the normal manner by the actuating roller.

The present invention provides novel and improved means for mounting and clamping the cam yokes in position on the keyboard frame whereby they can be locked and unlocked by means common to the plurality of cam yokes and when unlocked for visual inspection while the keyboard mechanism is running or in operation they will be retained in operative position although supported so that they may be readily exchanged, each cam yoke independently of all of the others.

To this and other ends, the invention consists in certain improvements and combinations and arrangements of parts, all as will be hereinafter more fully described the features of novelty being pointed out particularly in the claims at the end of the specification.

In the accompanying drawing:—

Fig. 1 is a perspective view of a section of a keyboard mechanism of the class referred to and embodying the present invention;

Fig. 2 is a transverse vertical section of a portion of the keyboard mechanism, showing the cam yokes clamped or locked in their normal operative positions;

Fig. 3 is a view similar to Fig. 2 but showing the cam yokes in unlocked condition and one of the cam yokes partially removed; and

Fig. 4 is a detail perspective view of the

retaining means for one of the rows of cam yokes.

Similar parts are designated by the same reference characters in the different figures.

- 5 The invention is shown in the present instance applied to a keyboard mechanism of the general class hereinbefore referred to wherein 1 represents the stationary cross members of the keyboard frame, 2 represents the front and rear rubber covered rollers which are journaled in the keyboard frame and are driven continuously during the operation of the machine as usual in keyboard mechanisms of this class, 3 represents the cam yokes each having a toothed cam 4 rotatably mounted therein between its ends, the cam yokes being arranged in front and rear rows as usual, one end of each cam yoke being connected by a pivot 5 to a bearing or mounting block 6 on which the cam yoke is supported on the keyboard frame, and 7 represents the reeds which rest on the other or free ends of the respective cam yokes and are forced upwardly by the operation of the respective cam yokes under the action of their cams to actuate the matrix controlling escapements of the magazine, as is usual in keyboard mechanisms of this class. The ends of the cam yokes opposite 30 to their pivoted ends are normally supported in elevated position with the cams 4 out of contact with the respective actuating rollers by triggers 8 which are pivoted in the keyboard frame, and these triggers are operated to release the respective cam yokes and permit the cams therein to engage the actuating roller, by the usual vertically movable key bars 9 which are guided by the upper and lower toothed bars 10 and 11 and by 40 the usual banking bar 12, these key bars being lifted to release the cam yokes by depression of the corresponding key levers of the keyboard, one of which key levers 13 is shown. As usual in keyboard mechanisms of this class, when a cam drops into engagement with the roller 2 and is rotated thereby to lift the cam yoke and the respective escapement actuating reed, the upward force applied by the cam to swing the cam yoke upwardly must be sustained by the pivot 5 which acts as a fulcrum about which the opposite or reed lifting end of the cam yoke swings.
- 55 The present invention provides means whereby the bearings 6 carrying the cam yoke pivots 5 are removably mounted on the keyboard frame and retained thereon so that any one of the cam yokes may be removed independently of the remainder while 60 at the same time the cam yokes will be held in position on the keyboard frame so that they may be operated by the actuating rollers without displacement, and this invention also provides means for effectively locking or 65 securing the cam yokes in operative posi-

tion or against removal from the keyboard frame. In the preferred construction shown, a vertical side of each frame cross member 1 is formed with a longitudinally extending rib 14 and the vertical face of each bearing or mounting block 6 is formed with a corresponding recess 15 into which the rib 14 is adapted to fit when the bearing or block 6 is in its proper operative position in the frame. A bar 16 is secured by a suitable number of screws 17 to each cross member 1, it forming a channel 18 between it and the side of the cross member 1 against which the bearings or blocks 6 are applied, and a spring bar 19 is fitted into said channel and is formed with a flat base portion which is secured to the bar 16 by a suitable number of screws 20. This spring bar, which is preferably of channel form, has an upturned side or flange 21 which is provided with a series of equally spaced tongues 22 which are tapered or bevelled at their upper ends, and the opposite upturned side of this spring bar is slotted down to its flat base to form a series of equally spaced tongues 23 having 90 outwardly turned lips 24 at their upper ends, the tongues 23 being located opposite to the tongues 22 but being somewhat wider than the tongues 22.

95 The bearings or mounting blocks 6 have slots 25 extending upwardly therein from their lower ends and when these bearings or mounting blocks are placed in position in the frame, these slots will receive the tongues 22 of the spring bar 19 which are somewhat less in width than said slots, the tongues 22 thus serving to properly space apart the cam yokes. When the bearings or mounting blocks 6 are in place in the frame, the tongues or fingers 23 bear against them at the side thereof opposite to the rib 14 and thereby hold the bearings or mounting blocks yieldably in vertical position and in engagement with said rib. The portion of the bar 16 opposite to the cross bar 1 of the frame is formed with a longitudinal groove or channel 26 which extends throughout the length of this bar and this channel serves as a bearing for a rotatable clamping or locking bar 27. This locking bar is formed at one side with a flat face 28 which extends throughout its length, and the locking bar may be rotated by a handle 29 fixed to one of its ends either into the position shown in Fig. 2 so that the unflattened portion of this bar bears against the tongues or fingers 23 or it may be rotated into the position shown in Fig. 3 so that the flattened face of the locking bar is opposite to the tongues or fingers 23. 110

115 The operation is as follows: when the locking bar 27 is turned to the position shown in Figs. 1 and 2 so that its flat face 28 is out of contact with the spring bar tongues or fingers 23, the lips 24 at the tops of the tongues 23 will be pressed firmly against all 120

125

130

the cam yoke bearings or mounting blocks 6 and will thereby hold these bearings or blocks securely in place in engagement with the rib 14 which locates them vertically and the tongues 22 which position them the proper distance apart in the direction of the row. However, if the handle 29 is turned to rotate the locking bar 27 so that its flat face 28 engages the tongues 23, the pressure of the lips 24 against the bearings or blocks 6 will be relaxed, but the tongues 23 will remain in engagement with the bearings or mounting blocks 6 by virtue of the springy material of the spring bar 19. The cam yoke bearings or mounting blocks 6 will therefore remain in place, the amount of relaxation of the pressure thereon by the spring tongues 23 being insufficient to allow the bearings or blocks 6 to disengage from the rib 14 under the lifting force applied to the cam yokes by the actuating roller 2 and the cams 4 when the latter come into action. The keyboard therefore may be run under power in the usual manner while the operator may visually examine the action of the cams without danger of displacement of the cam yokes in any way, and one or more of the cam yokes may be adjusted or removed without accidental displacement of the other cam yokes and which displacement, if it occurred, would result in much difficulty and delay before the keyboard could be restored to its proper operative condition. To remove a cam yoke, it is only necessary to draw the bearing or mounting block 6 rearwardly at the top against its spring tongue 23 sufficiently far to disengage the bearing or block from the rib 14 on the keyboard cross bar, as shown diagrammatically in Fig. 3, and then lift the yoke upwardly. To replace the yoke, the bearing or mounting block 6 can be readily inserted over the tapered tongue 22 to guide it downwardly into place until it rides over and snaps into engagement with the rib 14, this rib being bevelled along its upper and lower edges to permit the bearing or mounting block 6 to easily slide over it upon withdrawal or insertion. By swinging the handle 29 to bring the unflattened portion of the locking bar 27 into engagement with the tongues or spring fingers 23, as shown in Fig. 2, these tongues or fingers are forced with greater pressure against the bearings or mounting blocks 6, thereby securely clamping or locking the bearings or mounting blocks in fixed operative positions in the keyboard frame. By mounting the locking bar in the position shown, it avoids obstructing the view of the operator in examining the cam yokes or any of the other parts of the keyboard mechanism, whether in its locking or releasing position.

I claim as my invention:

1. In keyboard mechanism for typographical machines comprising a frame, a plu-

rality of cam yokes, and power means for actuating the cam yokes, yieldable means for removably mounting the cam yokes in said frame while retaining them in operative relation with said power means, and means acting on said mounting means for locking said cam yokes against removal. 70

2. In keyboard mechanism for typographical machines comprising a frame, a cam actuating roller therein, and a plurality of cam carrying yokes arranged to be actuated by said roller, means for yieldably and removably holding said yokes individually in said frame in operative relation with said roller, and means acting on said holding means and common to said plurality of yokes for securing them against removal. 75

3. In keyboard mechanism for typographical machines comprising a frame, a cam actuating roller therein, and a plurality of cam carrying yokes arranged to be actuated by said roller, means for individually and removably holding said yokes yieldingly in said frame in operative relation with said roller and permitting removal of any of said yokes independently of the holding means of the remainder thereof, and means common to said plurality of yokes and acting on said holding means for securing them against removal from said frame. 80

4. In keyboard mechanism for typographical machines comprising a frame, a cam actuating roller therein, and a plurality of cam carrying yokes to be actuated by power from said roller, bearings for pivotally supporting said yokes, means individually holding said bearings in position on said frame to withstand the power applied by the roller to said yokes to actuate them but yieldable to permit individual removal of the yokes from the frame, and means common to the plurality of yokes for retaining them against removal from the frame. 100

5. In keyboard mechanism for typographical machines comprising a frame, a cam actuating roller therein, and a plurality of cam carrying yokes arranged for actuation by power from said roller, bearings for pivotally supporting said yokes and removably engageable with the frame, yieldable fingers engaging said bearings individually and holding them in position on the frame to withstand the force applied to the yokes by said roller but permitting individual removal of the yokes from the frame, and means to act on said fingers to hold said bearings against removal from the frame. 110

6. In keyboard mechanism for typographical machines comprising a frame, a cam actuating roller therein, and a plurality of cam carrying yokes arranged in said frame for actuation by power from said roller and having bearings pivotally connected thereto, a rib and cooperating recesses being provided between the frame and said bearings to re- 120

movably position said bearings on said frame, spring fingers acting individually on said bearings to retain said yokes in operative position and to sustain the power applied thereto by said roller, said fingers being yieldable to permit disengagement of said rib and recesses and individual removal of said yokes from the frame, and means common to the plurality of cam yokes for retaining them against removal from the frame.

7. In keyboard mechanism for typographical machines comprising a frame, a cam actuating roller therein, a plurality of cam carrying yokes arranged in said frame for actuation by said roller, and bearings pivotally connected to the yokes and engageable with the frame, a series of spring fingers engaging the bearings of the respective yokes and holding them in operative position in the frame but permitting individual removal of the bearings therefrom, and a member operative to apply pressure to said fingers to clamp the bearings against removal from the frame.

8. In keyboard mechanism for typographical machines comprising a frame, a cam actuating roller therein, and a plurality of cam carrying yokes arranged in said frame for actuation by said roller and having bearings pivotally connected thereto and engageable with the frame, a series of spring fingers arranged to press against the respective bearings of the cam yokes to removably hold them in operative position on the frame, and a locking member operative on said fingers to increase their pressure against the bearings and thereby secure them against removal from the frame.

9. In keyboard mechanism for typographical machines comprising a plurality of cam yokes, a frame, and bearings removably engageable with the frame for pivotally supporting the yokes thereon, a series of spring fingers on the frame pressing against the respective bearings to retain them in engagement with the frame, and means to act on said fingers to increase or relax the pressure thereof against the bearings.

10. In keyboard mechanism for typographical machines comprising a frame, a plurality of cam yokes, and mounting blocks removably mounted in the frame and pivotally connected to said yokes for mounting them in the frame, said blocks having slots in their lower ends, a member secured to the frame and having a series of longitudinally spaced upwardly extending tongues to removably engage the slots in the respective mounting blocks and thereby space the yokes apart in the frame, and having yieldable means thereon to engage said mounting blocks and removably retain them in mounted positions in the frame.

In testimony whereof I have hereunto set my hand.
